PAPER-WEB-CONNECTING MECHANISM FOR PRINTING PRESSES.

Application filed June 25, 1926. Serial No. 118,487.

Our invention relates to improvements in means for connecting rolls of paper webbing in printing presses.

The main object of the invention is to provide improved means for substituting a fresh roll of paper and effecting its attachment to the web of an exhausting roll without stopping the operation of the press.

Another object of the invention is to provide a mechanism whereby the core-roll from which the web is becoming exhausted may, while still feeding the paper, be displaced from its normal operating position to make room for the positioning of a fresh roll.

15 A further object of the invention is to position a fresh roll of paper for a printing press while the old roll is still operating, and to start rotation of the fresh roll by the running web before uniting the new web with the old, then effecting the union of the two webs while they are in motion and finally cutting the web of the exhausting roll, and

20 Another object of the invention is to provide means for substituting new rolls of paper for old rolls on printing presses having a plurality of decks without stopping the operation of the press.

With these and other objects in view the invention is illustrated in the accompanying drawings, wherein,—

25 Fig. 1 shows in side elevation, an end portion of the press frame with the roll supporting arms together with the improved mechanisms associated therewith.

30 Fig. 2 illustrates, on an enlarged scale, a cross-sectional detail just above the axis of the lowermost roll to show the parts below, the section being taken on the line 2—2 of Fig. 1.

35 Fig. 3 shows a vertical elevation of the mechanisms at the inner side of one of the end frames of the press as the same would be viewed on the line 3—3 of Fig. 2.

40 Fig. 4 illustrates a vertical sectional detail through one of the roll-supporting arms and the carriage track-rail as viewed on the line 4—4 of Fig. 3.

45 Fig. 5 shows a vertical elevation of a portion of the end frame of the press to illustrate a portion of one of the vertical rack-bars and its guide bracket showing the same as if viewed on the line 5—5 of Fig. 3.

50 Fig. 6 illustrates a horizontal sectional detail through the same parts,—the section being taken on the line 6—6 of Fig. 3.

Fig. 7 shows a sectional plan of the devices as viewed below the line 7—7 of Fig. 1.

Fig. 8 illustrates in vertical elevation, one of the vertical rack-bars in the normal position but with one of its lifting-arms released and in readiness to swing under the spindle of the roll when the rack-bar begins its upward movement.

Fig. 9 shows a similar view of the rack-bar,—the latter being in the elevated position however, and the lifting-bar swung back against the side of and latched to the rack-bar.

Fig. 10 illustrates a cross-sectional detail through the same parts,—the section being taken on the line 10—10 of Fig. 8.

Fig. 11 shows another side elevation of the frame and one of the roll-supporting arms together with the devices for automatically effecting the tripping of the cutter and showing the fresh roll sustained by the carriage and on its way toward the normal roll bearings at the inner ends of the arms.

Fig. 12 illustrates the cutter frame and tripping devices as viewed from above and on the line 12—12 of Fig. 11.

Fig. 13 shows a vertical elevation of the devices disclosed in Fig. 11, but viewed from the line 13—13 of Fig. 11.

Fig. 14 illustrates in side elevation, the movable brake and core-roll aligner which operates on the end of the core-roll after the latter has been elevated to make room for the fresh roll, and

Fig. 15 shows the hand wheel adjustment for the aligner in top view.

Referring to the drawings, and particularly Figs. 1—2—3 and 11 thereof the numeral 20 designates a vertical end bar of the press frame at a feed-end of the press, 95 said bar frequently carrying a plurality of horizontally-extending arms 21.

These arms 21, are arranged in pairs, one pair being located in a different horizontal plane from each of the other pairs, and each pair of arms being utilized to sustain paper rolls for a certain deck in the press.

In the present instance (Fig. 1) the press is presumed to have three decks, and while this is not essential to the invention, there are certain structural features of the invention which are designed to cooperate with devices for any one of the plurality of decks.

Each arm 21 is provided at its inner side with a plurality of bracket plates 22, which

latter extend horizontally therefrom and these bracket-plates sustain inverted T-shaped rails 23,—the brackets having vertical slots 24, through which bolts 25, extend freely and then screw into the rails so that said rails may have a horizontal sliding movement on the brackets in a direction lengthwise of the rails.

These movable track-rails 23 have down-turned ends 26 with stop plates 27 near the ends thereof, as clearly seen in said Figs. 1—2—3 and 11 of the drawings, which down-turned ends terminate slightly in front of but in a plane below concave bearing recesses 28, that are provided in the upper edges of the arms 21.

At the outer ends each roll-supporting arm 21, is provided with a pivoted tongue extension 29 and to each of these pivoted extensions, there is pivoted one end of a lever 30 while the opposite end of each lever 31, is pivotally attached to a swinging bar 31. These swinging-bars 31 have one end pivoted to the outer side of the arms 21 while the depending end of each swinging-bar has a slot 32 therein.

A plate 33 is secured to the under side of the rail 23, and each plate is provided with a pin or stem 34, which projects horizontally therefrom and extends through the slotted end of the swinging lever 31.

By means of the lever 30, lever 31 and pins 34, the slide rails 23 are caused to be retracted or moved inwardly at the inner sides of the arms 21 as the tongues 29 are swung up.

The purpose of this construction is to permit both the tongue-extensions and the rails to be retracted and moved inwardly at the side of the arms to get them out of the way while fresh rolls of paper are being elevated past lower to upper decks.

By reference to Figs. 2—3—4 and 11 of the drawings, it will be noted that each track-rail 23 is provided with a carriage 35 and that each carriage is mounted on rollers which straddle the center web of the T-rail and roll on said rail.

It will further be noted that each carriage has a bearing block 36 thereon which latter has a normal position slightly above the upper horizontal edge of the roll-supporting arms because these bearing-blocks are provided to support the ends of the spindles which carry the fresh or full rolls and these rolls are to be advanced to the operating position by the carriages without rotating them as they advance until they are dumped into the bearing recesses 28. This feature will presently be more fully explained.

Each carriage is connected by an operating cable 37 which cables are lead around guide pulleys 38 and also around pulleys 39 that are carried by a head 40 on the outer end of a horizontal piston-rod 41,—the pis-

ton rod having a head 42 that is movable by fluid pressure in a cylinder 43, which in this instance, is located at the base of the press between the two vertical bars 20 of the frame, as can be seen in Figs. 1 and 2 of 76 the drawings.

It is believed to be obvious that when the piston 42, is made to travel in one direction in the cylinder 43, the cables will be drawn and the carriages 35, on which the spindles 75 carrying the fresh paper rolls are sustained, will be moved or advanced toward the normal bearing recesses 28 at the inner ends of the arms 21.

The fluid pressure to and from the cylinder 43 is conducted through a pipe 44, which is controlled by a three-way valve 45, as indicated in Fig. 2, of the drawing.

By reference to Fig. 2 of the drawing, it will be noted that the fresh roll of paper 85 46 is mounted on a spindle 47, and that the spindle is seated in the bearing-blocks 36 on the carriages 35.

It will also be noted that one end of this spindle 47 carries a grooved wheel 48, which may be termed the normal brake-wheel, while the opposite end of said spindle carries another grooved wheel 49 and also a collar 50 having a pin 51 projecting therefrom.

This latter grooved wheel 49 and the collar 50 with its pin 51 are novel features with us and perform useful functions as will presently be more fully explained.

Obviously, a fresh roll of paper cannot be advanced and placed in the bearings where the spindle of the exhausting roll is located without first displacing the exhausting roll and as our mechanisms operate without stopping the web of the exhausting roll, it is apparent that the exhausting roll or core as we call it must be moved while still unwinding to make room for the placing of the fresh roll in the normal bearings 28.

The mechanism for displacing the operating exhausting roll will therefore now be explained, reference being made particularly to Figs. 1—3—5—6—8 and 9 of the drawings.

It is of course to be understood that in Fig. 1, the mechanism is viewed from one side of the press while in Figs. 3—8—9 and 11, the views are all from the opposite side of the machine.

At the inner side of each vertical end-bar 20 of the press frame, we provide a vertical rack-bar 52, which extends from a point below the lowermost deck-arms to a point above the uppermost pair of deck-arms. 125 These vertical rack-bars are guided at intervals between their upper and lower ends by suitable cross guide-bars 53.

The upper ends of these vertical rack-bars 52 are connected to the lower ends of 130

piston rods 54, (see broken lines in Fig. 1) which later have pistons 55, that operate in vertical cylinders 56. Fluid pressure pipes 57, serve to provide the means for actuating the pistons,—the pipes in practice leading down to a point near the floor where valves are provided (similar to the valve 45) to conveniently control the pressure.

While we have in practice made use of 10 rack bars 52, it is not essential that these bars have racks, it being necessary only that some means be provided to operate the bars vertically and also that the two bars at opposite sides of the press be moved in unison.

We have therefore, in this instance, provided rack-teeth 58 on these bars 52 and we connect the rack on the bar at one side of the press with a pinion 59, and engage this 20 pinion with a gear 60 on one end of a horizontal cross-shaft 61, which latter extends across the press and has another gear 60 and pinion 59 which engages the rack at that side.

25 Thus the racks 58, pinions 59, gears 60 and shaft 61 merely serve to connect the rack-bar 52 at one side of the press with the other rack-bar at the opposite side of the press to insure a like vertical movement to 30 both rack-bars.

No matter whether the bars 52 be rack-bars or not, they extend vertically at opposite sides of the press and move vertically together and pass the inner ends of the several pairs of deck-arms 21.

40 We provide this vertical movement of the bars 52, for the purpose of effecting the displacement of any one of an exhausting paper roll or core roll from the normal bearings 28 of any one of the decks without stopping the revolution of that core-roll and to make room for the new roll before we connect the new web with the exhausting web, and we effect this operation by means 45 of a novel arrangement of core-lifting arms which the vertical bars actuate, as will now be explained.

By reference more particularly to Figs. 50 8 and 9 of the drawings, although the mechanism is also disclosed in Figs. 1 and 3, it will be noted that each vertical bar 52 is provided in this instance, with a plurality of swinging or lift-bars 62.

These lift-bars are spaced vertically on 55 the vertical bars so as to provide a pair of lift-bars for each deck,—one lift-bar being on the vertical bar at one side of the press and the other lift-bar being on the vertical bar at the opposite side of the press, and 60 both being arranged in the same horizontal plane, because one is to engage one end of the core-roll spindle that is to be displaced while the other lift-bar is to engage the opposite end of the same spindle.

65 Each lift-bar 62, has its lower end 63,

pivotaly attached to the vertical bar 52 and near its upper end each lift-bar has an inclined bearing-slot 64, with a laterally extending prong 65, at the entrance and under side of said slot.

70 Each lift-bar 62 has a latch device 66 which is designed to normally hold said bar in the vertical position at the side of and to the vertical bar 52, as in Fig. 9 of the drawings, and a spring plate 67 attached to the vertical bar 52, constantly presses against the lift-bar and will press the upper end of the lift-bar laterally to the position shown in Fig. 8, when the latch 66 is released.

75 The upper end of each lift-bar 62 is connected by a link 68 to one end of a lever 69 while the other end of said lever is pivotaly secured to a stationary bracket plate 70 at the side of the vertical frame-bar 20, therefore when the lift-bar 62 is unlatched, its upper end will swing laterally to the position shown in broken lines in Fig. 8, which position presents the prong 65 beneath the bearing 28 and the spindle 47 of the core-roll 46. This takes place before there is any upward movement imparted to the vertical bars 52.

80 When the fresh roll 46 is mounted on the carriages 35, it is so placed thereon that the free end edge 71 of the web will have position at the upper left hand quarter of the roll circumference as viewed in Figs. 3 and 11 and this edge is provided with an application of glue 72.

85 When the fresh roll is placed on the carriages and the circumferential position of the end edge 71 properly located, the collar 50 on the end of the spindle 47 of the same roll is set so the pin 51 will project radially on a line at the rear of the edge 71 of the roll so that as the carriage moves the fresh roll forward the free edge 71 of the web will be located to the rear of the vertical center while the pin 51 will be at the rear of 90 that free edge.

95 By again referring to Fig. 1 of the drawing, it will be noted that at the side of the vertical bar 20 of the press frame, there is a head 73 having a brake bar strap 74 at 100 each end thereof and a brake shoe 75, is attached to each bar-strap.

105 This structure is not new with us and forms no part of our invention, but the purpose of these brake devices is to fit about the ground wheel 48 on one end of the spindle 47 while the latter is seated in the normal bearings 28 and simply clamp the wheel sufficiently to prevent the running roll from gathering momentum and feeding the web 110 too fast.

115 This brake mechanism is disconnected from the grooved wheel 48 when the running roll is becoming exhausted, and in its stead we apply at the opposite end of the 120

spindle an improved brake device which we have designed to move upwardly with the core-roll as the latter is displaced, to make room for the fresh roll.

5 This new brake mechanism is illustrated in Figs. 14 and 15 of the drawings to which attention is now directed.

On the vertical end-bar 20 of the press frame, we provide a bracket 76 which carries a horizontal screw-threaded rod 77. The outer end of this rod is provided with a hand wheel 78 by means of which the rod may be rotated. On this threaded rod we mount a head 79 (see Fig. 15) which head has a screw-threaded bore through which the rod screws.

Obviously, by turning the hand wheel 78 and rod 77, the head 79 may be moved horizontally on the rod the distance of a few inches for a purpose that will presently be explained.

Two guide bars 80, are attached to the head 79 and these bars are connected at their outer ends by a cross-head 81.

25 On the rods 80 we mount a carriage 82 so the latter may travel freely on the rods between the heads 79 and 81, and this carriage pivotally sustains two brake-straps 83 while a suitable coupling 84 is provided to connect the straps.

The carriage 82 may be adjusted in a vertical plane by turning the hand wheel 78 and causing the head 79 to move horizontally on the rod 77, and as said head 79 may readily be turned on the rod 77, the latter, with the carriage 82 thereon may be swung down to present the brake-straps 83, in vertical alinement with the grooved wheel 49 on the spindle of the roll that is turning in 40 the bearings 28 prior to the elevation and displacement of that running roll as its web is becoming exhausted in order to make room for the fresh roll whose web is to be united with the exhausting and elevated running roll.

45 It should be understood that this latter brake device is designed to be engaged with the grooved wheel 49 and then the brake device 73—74 on the opposite end of the same spindle may be disconnected from the grooved wheel 48, so that as the exhausting running roll is transferred from the bearings 28 and moved upwardly to the position 50 in Fig. 11 of the drawings, the traveling and movable brake 83, may swing up with the exhausting roll and maintain the proper tension thereon.

We have found in practice that during the shifting of the running core roll from the lower to the upper position, the web may not be delivered accurately to the press and to meet this and maintain proper alinement, we provide the screw rod 77 and the threaded bore in the head 79 so that the en-

tire running core may be shifted in a horizontal plane by shifting the position of the rods 80, carriage 82 and brake straps 83.

Presuming now that the running core-roll has been elevated the next operation is to place the fresh roll in the bearings 28 70 just vacated by the running core roll.

The carriages 35, sustaining the fresh roll are next drawn forward by the cables 37 (Fig. 2) and when the inner inclined end 26 of the rack-rails 23 are reached, the carriages tilt and dump the roll and spindle therefrom and the spindle-ends drop into the normal bearings 28 at the inner ends of the deck arms.

This operation places the fresh roll in the 80 normal bearings 28 beneath the core roll and web running therefrom but the fresh roll is stationary and has the free edge 71 of its web coated with glue 72 and pointing upwardly at the rear portion of the circumference of the roll as shown in Fig. 3 of the drawing.

At this same moment, the pin 51 on the collar 50 that is mounted on the spindle 47, 90 preferably extends substantially horizontally but behind the free edge 71 of the web.

The precise locations of the free end edge 71 of the web and the pin 51 on the collar depend entirely upon the speed at which it is desired to drive the running web from the core-roll at the time the union with the fresh web is to be made but in practice we slow the press down and thus reduce the speed of travel of the exhausting web so as to avoid sudden strain on the running web 100 that might cause that web to tear by requiring the fresh roll to suddenly start rapid unwinding rotation.

In accordance with our invention we utilize the running exhausting web to set up 105 rotation of the fresh roll and then we unite the webs and cut the exhausted web allowing the cut exhausted web to draw the fresh web through the press.

The next step therefore in the operation is 110 to set the new or fresh web into rotation and this we do by means that will now be explained, reference being made particularly to Figs. 1—3 and 11 of the drawings.

Extending crosswise of the press at the 115 forward vertical sides of the end bars 20 of the press frame, we provide a horizontal rock-shaft 86,—the same being sustained in suitable bracket bearings 87 and on this shaft we mount two spaced apart levers 88, 120 which latter extend upwardly at opposite ends of the roll of paper 46.

The upper ends of the levers 88 sustain a soft composition roller 89, which roller extends horizontally across and above the 125 running exhausting web which we designate 90 in Figs. 3 and 11 of the drawings.

The rock-shaft 86 also has actuating levers

91, which depend therefrom and which have a horizontal pin 92 extending laterally from the lower end thereof.

The pin 92, when the lever 91 is in the normal position as in Fig. 1, is engaged by a vertical pin 93 to hold the lever down, but when it is desired to start the fresh roll 46 to revolving immediately prior to the union of the two webs, the pin 93 is withdrawn and lever 91, is swung laterally, thereby rocking shaft 86 and moving the horizontal composition roller 89, against the upper side of the running web 90 thereby depressing the running web until it comes into frictional contact with the circumference of the fresh roll 46.

During this operation, the operator of the lever 91 varies the pressure of the composition roll until the friction of the running web causes the fresh roll to revolve.

As the fresh roll begins to revolve the free edge 71 of the web thereon approaches the contact point between the running web 90 with the fresh revolving roll and as the said edge 71, with the glue 72 on its upper surface passes under and in contact with the running web, the two webs are immediately united.

While rotation of the fresh roll is being set up and the union of the two webs made, the spindle 47 carrying the fresh roll is also being revolved and in turn is revolving the collar 50 and the pin 51 thereon. This pin 51 is therefore now about to perform a useful function of operating mechanisms that will cut the running web, as will now be explained, reference being made particularly to Figs. 3-7-11-12 and 13 of the drawings.

As collar 50 revolves, it carries the pin 51 with it and the relative position of this pin with respect to the glued edge 71 of the web is such that the pin trails behind such edge so that after the glued edge is united with the running web 90, the pin 51 will, during its swing, strike the lower free end 94, of an actuating lever 95 to rock the latter.

The lever 95, is pivoted at 96 to one of the vertical bars 20 of the press frame and its upper end is pivotally connected to one end of a rocking slide-bar 97 which latter extends through a guide or keeper 98 and has a down-turned hook 99, on its rear end.

The under side of the slide bar carries a pin or projection 100 which latter, when the slide bar is drawn outwardly, engages a cam plate 101 and thereby causes the hook-end 99 of the bar to be raised, for a purpose that will presently be explained.

Bearing brackets 102 are attached to the press frame and these brackets support a horizontal rock-shaft 103.

An arm 104, is carried on the outer end of the rock-shaft 103 and said arm extends upwardly and carries a laterally-projecting

pin 105, with which the hook 99 on the sliding lever 97 normally is engaged.

The rock-shaft 103 also carries a counter-weight 106 which weight is lifted as lever 97 is drawn outwardly to swing the arm 104; to rock the shaft 103 and by moving sprocket chain 117, tilt knife or cutter 115, as will presently be better understood and as these operations take place, the weight 106 will be elevated so that as soon as the cutter has been actuated the cam 101, will lift lever 99 and disengage the pin 105, so the counter-weight 106 can return the parts to the normal position.

In other words, hook 99, by engaging arm 104, holds the rock-shaft in one position against the action of the weight 106, which weight, when the hook 99 disengages arm 104, causes the rock-shaft 103 to make a partial rotation, for a purpose which will now be explained.

The inner end of the rock-shaft 103, carries a sprocket wheel 107, which latter is fixed to said shaft and has only a partial rotation with said shaft when the latter is rocked.

Below the rock-shaft 103, the frame of the press carries a horizontal angle-bar 108 which extends all the way across the press frame from one vertical bar 20 to the other. This angle bar carries two brackets 109 and these brackets pivotally sustain two long bell-crank shaped arms 110,—one leg 111 of each arm extending up and under the shaft 61, while the other leg 112, of each arm extends outwardly between the deck arms 21, and carry a cutter frame 113. This cutter-frame carries a horizontal shaft 114, to which a cutter-plate 115, is attached.

The end of the cutter shaft 114 extends through the leg 112, of the bell-crank shaped arm and this projecting end carries a sprocket 116 so that a sprocket chain 117 may pass around the sprockets 107 and 116 and rock the cutter shaft 114 each time the shaft 103 is rocked as the result of the pin 51 on collar 50 striking and actuating lever 94.

As cutter-shaft 114 is rocked, the cutter blade or plate 115, will be forced downward and through the running web 90 as shown in broken lines in Fig. 3 of the drawing.

After the running roll has been cut the spindle in the spent core roll will be engaged by a hoist device and lifted from the lift-arms after which the arms may be lowered by dropping the rack-bars 52 back to their normal positions and when doing this, the lift-arms will ride down over the ends of the spindle then in bearings 28 and thus swing the arms back until the latches 66 engage and retain them at the sides of the rack-bars.

Having described our invention, we claim,

1. In a paper web mechanism for printing presses the combination with means for normally sustaining a rolled web of paper while the latter is being fed to the printing press, of means for moving the roll from the normal sustaining means while the web is unwinding therefrom to make room for the reception of a fresh roll in said normal sustaining means, a braking means for the roll 70
 10 when it is carried by the normal sustaining means and a second braking means for the roll and movable with the roll as it is shifted from the normal sustaining means.
2. In a paper web connecting mechanism 75
 15 for printing presses the combination with means for normally sustaining a rolled web while the latter is being fed to the printing press, of reciprocating bars adjacent to each normal sustaining means, swinging means operated by the reciprocating bars for engaging an exhausting running roll and moving it from the normal sustaining means to make room for a fresh roll of paper, carriers for delivering a fresh roll of paper to 80
 20 the normal sustaining means, means for driving the fresh roll by the web of the moved running roll, a cutter and means operated by the rotation of the fresh roll for actuating the cutter.
3. In a paper web connecting mechanism 85
 25 for printing presses the combination with means for normally sustaining a rolled web while the latter is being fed to the printing press, of means for moving the roll from the normal sustaining means while the web is unwinding therefrom to make room for the placing of a fresh roll in the normal sustaining means, track-rails leading to the normal sustaining means, a carriage on each 90
 30 track-rail, said track-rails being arranged in spaced pairs with means at the inner ends for tilting the carriages to dump the fresh rolls so they may be sustained by the normal bearings, means for uniting the web of the fresh roll with that of the running roll and means for cutting the running roll.
4. In a paper web connecting mechanism 95
 35 for printing presses the combination with a press structure having bearing means for normally sustaining a rolled web while the latter is being fed to the printing press, of means for raising the running roll from the normal bearing means while the web is unwinding therefrom, means for moving a 100
 40 fresh roll of paper beneath the raised running roll and placing said fresh roll of paper in the said normal bearing means, means for uniting the web of the fresh roll with the web of the removed roll that is still running and means for cutting the old running web.
5. In a paper web connecting mechanism 105
 45 for printing presses the combination with a press structure having bearing means for normally sustaining a rolled web while the latter is being fed to the printing press, of means for placing a fresh roll in the 110
 50 said normal bearing means just vacated by the still running roll, means for revolving the fresh roll of paper by direct contact with the running web of the removed first-named roll and securing the two webs together and means for cutting the running web from the removed roll after the fresh roll has been placed in the normal bearing means.
6. In a paper web mechanism for printing 115
 55 presses the combination with a stationary bearing for normally sustaining a rolled web of paper while the latter is being fed to the printing press, of means for lifting the revolving roll and moving it laterally 120
 60 from the stationary bearing while the paper web is feeding therefrom, means for moving a fresh roll into the same stationary bearing, means for uniting the web of the fresh roll after it has been placed in said stationary bearing with the running web of the roll that has been moved from said stationary bearing and means for cutting the web of the running roll.
7. In a paper web connecting mechanism 125
 65 for printing presses the combination with a press structure having bearing means for normally sustaining a rolled web of paper while the latter is being fed to the printing press, of means for elevating the roll and lifting it bodily from the normal bearing means while the web is unwinding therefrom to make room below it for the placing of a fresh roll in the said normal bearing means, and a carrier for a fresh roll of paper, said 130
 70 carrier moving the fresh roll bodily in a horizontal direction and keeping the free edge of the web at a substantially definite horizontal plane while the roll is being moved to the said normal bearing means, said carrier placing the fresh roll in the said normal bearing means from which the exhausted roll has been removed.
8. In a paper web connecting mechanism 135
 75 for printing presses the combination with a press structure having bearing means for normally sustaining a rolled web of paper while the latter is being fed to the printing press, of means for moving the roll from the said normal bearing means while the web 140
 80 is unwinding to make room for the placing of a fresh roll in the said normal bearing means, a carrier for bodily moving a fresh roll of paper toward the said normal bearing means and means for dumping the fresh roll from the carrier into the normal bearing means from which the exhausted roll has been removed prior to the rotation of the fresh roll.
9. In a paper web connecting mechanism 145
 85

- for printing presses the combination with a press structure having bearing means for normally sustaining a rolled web while the latter is being fed to the printing press, of 5 means for moving the roll from the normal bearing means while the web is unwinding therefrom to make room for the placing of a fresh roll in the said normal bearing means, a carrier for bodily moving a fresh 10 roll of paper toward and placing it in the said normal bearing means, means for revolving the fresh roll by pressing the web of the removed roll back toward the normal bearing to bring it in contact with the web 15 of the new roll that has been placed in said normal bearing and to effect a union between the webs of the removed and the substituted rolls and means for cutting the web of the removed roll.
10. In a paper web connecting mechanism for printing presses the combination with a press structure having bearing means for normally sustaining a rolled web while the latter is being fed to the printing press, of 20 means for moving the roll from the said normal bearing means while the web is unwinding to make room in the said normal bearing for the placing of a fresh roll therein, a carrier for bodily moving the fresh roll 25 of paper toward and dumping it in the said normal bearing means, means for revolving the fresh roll by pressing the web of the removed roll back toward the normal bearing and to effect a union between the webs 30 of the two rolls, a cutting mechanism and means at the end of the fresh roll spindle for effecting an operation of the cutting mechanism.
11. In a paper web connecting mechanism for printing presses the combination with a 40 press structure having bearing means for normally sustaining a rolled web of paper while the latter is being fed to the printing press, of means for moving the roll from the said normal bearing means while the web is unwinding therefrom and still feeding to the press to make room for the placing of a fresh roll in the same normal bearing means, means for longitudinally adjusting the moved old roll to maintain its proper alignment with the press devices, means for placing a fresh roll in the said normal bearing means and means for uniting the web of the new roll after it has been placed in the 50 normal bearing means with the running web of the roll that has been removed from the same normal bearing means.
12. In a paper web mechanism for printing presses the combination with a press structure having a plurality of decks from 60 which webs of paper are fed from separate rolls into the press, of normal bearing means at each deck of the press for sustaining rolls of paper that are feeding to the press, reciprocable means adjacent to each bearing means for engaging a running exhausting 65
- roll and moving it while running from the normal bearing means to permit a fresh roll to be inserted in its place in said normal bearing means, means for presenting a fresh roll of paper to the said normal bearing 70 means from which the running roll has been moved and means for uniting the web of the fresh roll with the web of the previously removed running exhausting roll.
13. In a paper web connecting mechanism for printing presses the combination with a press structure having bearing means for normally sustaining a rolled web while the latter is being fed to the printing press, of upwardly-movable swinging means adjacent to each of said bearing means for engaging an exhausting running roll and moving it upwardly and laterally from the said normal bearing means to make room for a fresh roll of paper in the said normal bearing means, means for placing a fresh roll in the same bearing means just vacated by the exhausting roll, a cutter mechanism, means on the end of the spindle of the fresh roll for actuating the cutting mechanism and means for operating the upwardly-movable swinging means.
14. In a paper web connecting mechanism for printing presses the combination with a press structure having bearing means for receiving and holding a rolled web of paper while the latter is being fed to the printing press, of tracks extending laterally from each bearing means, carriages movable on the tracks and sustaining the roll of paper to 100 carry it bodily to the said bearing means and means adjacent to each of said bearing means to cause the carriages to tilt and dump the roll into the bearing means.
15. In a paper web connecting mechanism for printing presses the combination with a press structure having a plurality of decks of a pair of track rails extending laterally from each deck, a pair of spindle supporting bearings at the inner ends of the track 105 rails for normally supporting a roll of paper while it is feeding to the press, reciprocating means extending vertically past the several decks at each side of the press and having pivoted arms at each deck, means for reciprocating said means to move the arms vertically and means for swinging the arms laterally as they move vertically to lift the roll of a running web at any deck and swing it away from the spindle-supporting bearings to make room for a fresh roll of paper 115 in the bearings just vacated.
16. In a paper web connecting mechanism for printing presses the combination with a press structure having a plurality of decks of a pair of track rails extending laterally from each deck, a pair of spindle supporting bearings at the inner ends of the track 120 rails for normally supporting a roll of paper while it is feeding to the press, reciprocating 125

ing means extending vertically past the several decks at each side of the press and having pivoted arms at each deck, means for reciprocating said means to move the arms vertically and link-bars pivotally connected with the swinging arms to swing the latter and the roll of the running web away from the spindle-supporting bearings to vacate the latter and permit a fresh roll to be placed 10 in said bearings.

17. In a paper web connecting mechanism for printing presses the combination with a press structure having stationary bearing means for normally sustaining a rolled web

15 while the latter is being fed to the printing press, of roll lifting-arms at each side of the bearing means, means for raising the arms past the bearing means to engage and raise the roll of paper to make room for a fresh 20 roll to pass thereunder to the normal stationary bearing and means for swinging the arms laterally as they are raised.

18. In a paper web connecting mechanism for printing presses the combination with a press structure having bearing means for 25 normally sustaining a rolled web while the latter is being fed to the printing press, of pivoted roll-lifting arms at each side of the bearing means, rack-bars for raising and lowering said arms and link-bars for swinging said arms as they are raised and lowered.

19. In a paper web connecting mechanism for printing presses the combination with a press structure having bearing means for 30 normally sustaining a rolled web while the latter is being fed to the printing press, of

roll-lifting arms at each side of the bearing means, means for raising said arms to engage a running roll in the bearing means and lift it therefrom, means for swinging said 40 arms as they lift the running roll from the bearing means and move its axial point rearwardly from the axis of the bearing means from which the roll was lifted, means for depositing a fresh roll of paper in the bearing means just vacated and means for depressing the running web of the lifted roll against the circumference of the fresh roll that has been deposited in the said bearing means. 45

20. In a paper web connecting mechanism for printing presses the combination with a press structure having bearing means for normally sustaining a rolled web while the latter is being fed to the printing press until the web is nearing the exhaustion point, of means for bodily lifting the roll from the bearing means while running and moving it rearwardly to permit a fresh roll to be moved beneath the lifted running roll and placed in the bearings vacated by the exhausting roll, means for depressing the web of the removed running roll until it contacts with the fresh roll and sets the latter into motion and splices the two webs, a knife structure and means carried on the spindle of the fresh roll for actuating the knife to cut the web of the exhausting roll. 50

In testimony whereof we affix our signatures.

THOMAS JOHANCEN.
EDWARD KEHOE.
